(57) **CLAIM**

The ornamental design for a navigation device as shown and described.

DESCRIPTION

FIG. 1 is a front, left, and top perspective view of a navigation device, showing my new design;
 FIG. 2 is rear, right, and bottom perspective view thereof;
 FIG. 3 is a front elevational view thereof;
 FIG. 4 is a rear elevational view thereof;
 FIG. 5 is a bottom plan view thereof;
 FIG. 6 is a top plan view thereof;
 FIG. 7 is a left elevational view thereof;
 FIG. 8 is a right elevational view thereof; and,
 FIG. 9 is a perspective view thereof, illustrated in an alternate configuration.

The broken lines in the drawings depict portions of the navigation device that form no part of the claimed design.
